UNITED STATES PATENT OFFICE

2,142,239

METHOD OF FORMING DETACHABLE DRILL
BIT SHANKS

Charles Edward Cook, South Porcupine, Ontario, Canada, assignor to International Detachable Bits & Equipment, Limited, Timmins, Ontario, Canada, a corporation of Canada

Application September 23, 1937, Serial No. 165,238

8 Claims. (Cl. 76—108)

My invention relates to improvements in methods of forming detachable drill bit shanks and an object of my invention is to devise a method for forming such shanks wherein no metal is removed from the drill steel stock from which the shank is fabricated thus resulting in a very considerable economy in the consumption of steel. A further object is to evolve a method wherein no special machines are necessary for forming the steel stock into a shank and consequently no specially trained operators are required, thus effecting additional economy in the cost of production, which method is further rendered even more economical due to the minimum number of heats and operations necessary, and due to the fact that no annealing of the shank is necessary as the end thereof for connection to the bit is formed by a forging operation instead of by machining as is the orthodox practice.

20 A still further object is to devise a method which may alternatively be employed to recondition damaged or worn shanks.

My method is particularly adaptable for forming the detachable bit shanks of the construction described in United States Patent No. 2,030,576, issued February 11, 1936, wherein the bit is connected to the shank by a dovetail tongue received into a dovetail slot in the shank end, and it is the fabricating of such construction of shank that I have illustrated in the accompanying drawings in which:—

Fig. 1 represents a side elevation of a drill steel stock showing a grinding wheel applied thereto for grinding the end of the stock perpendicularly to the longitudinal axis thereof.

Fig. 2 is a side elevation of the stock referred to in Fig. 1 illustrating it held between the upper and lower portions of a divided clamping die (shown in section) and its end about to be upset by a reciprocable dolly (shown in elevation).

Fig. 3 is a similar view to Fig. 2 only showing the dollying operation on the shank completed with the end of the shank upset into enlarged circular cross-section corresponding to that of the larger end of the interior of the divided die.

Fig. 4 is a cross-sectional view taken through the line 4—4 (Fig. 3).

Fig. 5 is a cross-sectional view taken through the line 5—5 (Fig. 3).

Fig. 6 is a similar view to Figs. 2 and 3 only showing a further dolly replacing that above referred to and having formed a straight walled slot in the end of the stock.

Fig. 7 is also a similar view to Figs. 2, 3 and 6 only showing a still further dolly having a re-

movable head with a dovetail shaped tip having formed the straight walled slot in the end of the stock or shank as it may now be termed into one of dovetail shape cross-section.

Fig. 8 is a perspective detail of the end of the dolly shown in Fig. 6, and

Fig. 9 is a similar view of the dolly of Fig. 7.

Like characters of reference indicate corresponding parts in the different views of the drawings.

In carrying out my method, as illustrated, I first square off the end of the stock A. I then place it between the upper and lower parts 1 and 2 of a divided clamping die, which parts are respectively attached to the ram 3 and lower die holding block 4 of a standard drill steel sharpener. With the stock A previously heated held firmly in place between the parts 1 and 2 of the divided die, I submit the end to the dollying operation of the reciprocable flat faced dolly 5 which may have a pointed centering tine 6 centrally disposed on its flat face, it being understood that the dolly 5 is mounted in the dollying attachment (not shown) of the drill steel sharpener with its longitudinal axis coincident with the longitudinal axis of the stock A.

Such dollying operation by the flat faced dolly 5 upsets the heated squared end of the stock A forcing it into the enlarged end 7, 8 of the interior of the divided die and causing it to fill the same as illustrated in Figs. 3 and 5 of the drawings wherein it assumes an enlarged form of circular cross-section B corresponding to the cross-sectional shape of the interior 7, 8 of such end of the divided die.

Thus the stock A is forged into a drill shank with an enlarged circular end. It now remains to form a transverse dovetail slot in the end of the shank to receive the dovetail connecting tongue of the detachable bit.

The flat faced dolly 5 of Fig. 2 is now replaced by another dolly 9 (illustrated in Figs. 6 and 8) having a raised diametrically disposed rib 10 with straight side walls and the enlarged end B of the shank is submitted to a further dollying operation wherein a transverse slot 11 with straight side walls is formed in the shank end B as illustrated in Fig. 6 of the drawings.

The shank is now removed from the divided clamping die and is reheated being subsequently placed again in the die and firmly clamped therein. A dolly 12 (Figs. 7 and 9) is substituted for the dolly 9 in the dollying attachment of the drill sharpener. Such dolly 12 is constructed in two pieces with its removable head 13 having a

transverse rib 14 of dovetail cross-section formed on its exposed end, the form of the rib being that of the slot in the shank which it is desired to form. The removable head 13 is inserted into 5 a bore 15 in the end of the dolly proper 12 which is itself secured in the dolly attachment.

The dolly 12 is now adjusted so that the rib 14 is inserted into the straight walled slot 11 of the shank end and such end is again dollyed by 10 such dolly with the result that the straight walled slot 11 is forged into a slot 16 of dovetail cross-section as illustrated in Fig. 7 of the drawings which is the ultimate and required shape thereof.

The dolly proper 12 is then removed leaving 15 the removable head 13 on the shank end. The shank is now removed from the divided die and the removable head, which is held to the shank end by the rib 14 being disposed in the slot 16, is tapped transversely wherein it is detached 20 from the shank end.

A method of forming detachable drill bit shanks of the type above described possesses the advantage that it is fabricated entirely by forging operations in a drill sharpener as usually employed in mines where such drills are primarily used. No expensive machines are required such as is the case with conventional methods which entail machining operations. Furthermore, my 25 method entails no wastage of steel such as conventional methods involving machining do, and there is a saving in heating and operations as well as in labour costs.

Consequently my method is particularly applicable for use in the steel shops of mines for 25 fabricating new drill shanks of the type set forth as well as for reconditioning used shanks which have become damaged or worn.

Although I have described and illustrated my method as being particularly adaptable to forming 40 detachable drill bit shanks of the type referred to in the above United States patent, it will be understood that such method may be employed for forming other types of detachable drill bit shanks by changing the design of the dollies 45 used.

What I claim as my invention is:

1. In a method of forming detachable drill bit shanks of the type in which the shank end is provided with a transverse dovetail slot for the 50 reception of the connecting dovetail tongue of a detachable bit, the steps which consist in clamping a previously heated drill steel stock between the parts of a divided die in a drill sharpener, said die having one end of its interior enlarged 55 and of circular cross-section, by a dollying operation of the dolly attachment of the drill sharpener upsetting the end of the stock disposed in the die so that it fills the enlarged end of the die and assumes its shape wherein a drill shank 60 with an enlarged circular end is constituted, by a further dollying operation forging a transverse straight walled slot in the end face of the enlarged end of the shank, and by a still further dollying operation forging such straight walled 65 slot into a slot of dovetail cross-section.

2. In a method of forming detachable drill bit shanks of the type in which the shank end is provided with a transverse dovetail slot for the 70 reception of the connecting dovetail tongue of a detachable bit, the steps which consist in clamping a previously heated drill steel stock between the parts of a divided die in a drill sharpener, said die having one end of its interior enlarged and of circular cross-section, by a flat faced dolly actuated by the dolly attachment of the drill

sharpener dollying the end of the stock disposed within the die wherein it is upset and fills the enlarged end of the die wherein a drill shank with an enlarged circular end is constituted, subsequently by a dolly having a diametrical rib with straight side walls on its end face dollying the enlarged end of the shank in the die wherein a straight walled slot is forged therein, and finally by a dolly having a diametrical rib of dovetail cross-section dollying the enlarged end of the shank whereby the straight walled slot therein is forged into a slot of dovetail cross-section. 5

3. A method as claimed in claim 2 wherein the shank is removed from the die after the straight walled slot has been forged in the enlarged end 15 thereof, is then reheated and again clamped in the die prior to the final dollying operation.

4. A method of forming detachable drill bit shanks of the type in which the shank end is provided with a transverse dovetail slot for the 20 reception of the connecting dovetail tongue of a detachable bit which consists in clamping a pre-heated drill steel stock having its end previously squared off perpendicularly to its longitudinal axis between the parts of a divided die having one 25 end of its interior enlarged and of circular cross-section in a drill sharpener, by a flat faced dolly dollying the end of the stock whereby it is upset and fills the enlarged end of the interior of the die wherein a drill shank with an enlarged circular end is constituted, by a dolly having a diametrical straight walled rib on its end face dollying the enlarged end of the shank in the die wherein a straight walled slot is forged therein, removing the shank from the die, reheating it, 30 firmly clamping it in the die again, by a dolly having a diametrical rib of dovetail cross-section on its end face inserted in the straight walled slot in the enlarged end of the shank dollying such shank end to forge the straight walled slot 40 into a slot of dovetail cross-section. 35

5. A method as claimed in claim 4 wherein the dovetail rib on the last mentioned dolly is provided on a removable head of the dolly proper, removing such dolly proper from its head after 45 the final dollying operation leaving the head attached to the shank end by means of the dovetail rib, removing the shank from the die and subsequently tapping the head transversely whereby its dovetail rib is displaced from the 50 dovetail slot in the shank end.

6. In a method of forming detachable drill bit shanks of the type in which the shank end is provided with a transverse dovetail slot for the 55 reception of the connecting dovetail tongue of a detachable bit, the steps which consist in dollying the end of an unfinished shank having a straight walled diametrical slot therein with a dolly having a removable head with a diametrical rib of dovetail cross-section on its exposed end 60 face by inserting said rib into the straight walled slot in the shank end, whereby the straight walled slot is forged into a slot of dovetail cross-section extending from one side to the opposite side of the shank wall, removing the dolly leaving the 65 removable head attached to the shank end by means of the dovetail rib in the dovetail slot, and tapping the head transversely to displace its dovetail rib from the dovetail slot in the shank end. 70

7. A method of forming detachable drill bit shanks of the type in which the shank end is provided with a transverse dovetail slot for the 75 reception of the connecting dovetail tongue of a detachable bit which consists in first forging a

- straight walled diametrical slot in the shank end extending from one side to the other side of the shank wall by means of a dolly having a straight walled diametrically extending slot forming rib, 5 subsequently subjecting the shank end to the dollying action of another dolly having a diametrical rib of dovetail cross-section inserted into the straight walled slot in the shank end whereby such straight walled slot is forged into a slot of dovetail cross-section, and finally moving the dolly provided with the diametrical rib of dovetail cross-section transversely to detach it from the formed slot of dovetail cross-section in the shank end.
- 15 8. In a method of forming detachable drill bit shanks of the type in which the shank end is pro-

vided with a transverse dovetail slot for the reception of the connecting dovetail tongue of a detachable bit, the steps which consist in forging the end of an unfinished shank having a straight walled diametrical slot therein extending from one side to the other side of the shank wall by means of a dolly having a diametrical rib of dovetail cross-section inserted into the straight walled slot whereby such straight walled slot is forged into a slot of dovetail cross-section, and 10 subsequently moving the dolly transversely to detach its rib of dovetail cross-section from the formed slot of dovetail cross-section in the shank end.

CHARLES EDWARD COOK. 15
